UNITED STATES PATENT OFFICE.

GEORGE F. HOLLER, OF CINCINNATI, OHIO, AND EMIL SCHMIDT, OF COVINGTON, KENTUCKY, ASSIGNEES TO THE MONITOR STOVE COMPANY, OF CINCINNATI, OHIO, A CORPORATION OF OHIO.

FURNACE-DRAFT-DOOR CONTROL.

Application filed May 14, 1921. Serial No. 469,675.

To all whom it may concern:

Be it known that we, GEORGE F. HOLLER, a citizen of the United States, and residing in Cincinnati, in the county of Hamilton, 5 State of Ohio, and EMIL SCHMIDT, a citizen of the United States, and residing at Covington, in the county of Kenton and State of Kentucky, have invented a new and useful Improvement in Furnace-Draft-Door 10 Controls, of which the following specification is a full disclosure.

Our invention relates to an improvement in furnace draft door controlling mechanism, for operating the doors at the register 15 of the furnace.

An object of the invention is to provide a furnace register with means for operating and controllably setting the draft doors of the furnace, whereby the draft door controlling mechanism is incorporated in the furnace structure. This offers many advantages in the manufacture and installation 20 of furnaces, and when applied to the floor register of the type of furnace commercially known as "pipeless," provides very 25 appropriate and convenient location for the draft door controlling mechanism and enables the standardizing of these parts for all installations.

Other objects of the invention relate to the construction of the draft door controlling mechanism, and to its combination with the floor register of the furnace, all of which will be more fully set forth in the description 30 of the accompanying drawing, forming a part of this application, and in the drawing like characters of reference denote corresponding parts throughout the several views, of which:

Fig. 1 is a side elevation of a hot-air furnace represented as of a "pipeless" type, with our improved draft control applied in position for use.

Fig. 2 is an enlarged side elevation of the lever mechanism as applied to the floor register grid for operating the draft doors.

Fig. 3 is a top plan view of a portion of the floor register.

Fig. 4 is a central vertical section of the lever mechanism and floor register plate.

Referring to the drawing, 1 indicates a hot-air furnace of the "pipeless" type in which the furnace air conductor casing 2 extends vertically from the top of the fur-

nace to the building floor above. The casing 2 terminates with a floor register or grid-plate 3, having a floor connection flush with the surface plane of the floor. The ash-pit door 4 of the furnace is provided with a draft door 5 and the furnace stack 6 pipe with a check draft door 7, as parts of a general hot-air furnace equipment. The functions of the draft doors are well known to the art and the improvement herein is directed to the operation and control 65 of the doors. The mechanism for operating the doors is arranged to provide for an alternate opening or closing of the doors or permitting both to be closed at the same time to meet the general requirements for 70 furnace draft regulation.

A chain or pull cord 8, at one end, connects the front draft door 5, and its opposite end with one arm of the bell crank lever 9, pivotally connected to a bracket screw 10, 75 dependently secured from the floor 11. The opposite or second arm of the bell crank lever 9 connects with one end of a cord or chain 12 as a cross connection, and the opposite ends of said chain connect with one 80 arm of a second bell crank lever 13 pivotally mounted upon a bracket screw 13^a dependently secured from the floor 11 appropriately above the check draft door 7. The second arm of the bell crank lever 13 connects with the draft door 7 by a chain or cord 14. Both draft doors are thus in operative connection, and while the arrangement shown is preferable, the connection 85 may be by means of a continuous cord or chain between the doors, guided over rollers to present an intermediate portion in a horizontal line for connection with the actuating mechanism therefor.

The register floor plate is provided with 90 a rectangular guide pocket 15, the base of the frame portion of the plate forming the pocket having an elongated slot 16 therethrough. A tread slide block 17 is slidably engaged in the pocket, the said block having 95 a rounded knurled or serrated upper face, providing a tread gripping surface to be engaged by the foot of the operator, for shifting the block. The block has its outer side recessed to provide a socket for an end of 100 a link 18 pivotally connected to the block by a pin 19. The link 18 projects through the slot 16 in the register floor plate and piv-

totally connects at 20 with the link 21 of the pivotally secured depending bracket 22, secured to the under side of the register floor plate. The link 18 is also loosely pivoted to the bracket by means of a pin 23 fixed to the bracket and extending through an oblong slot 24 in the link. A similar connection is provided for pivotally mounting the link 21 to the bracket, comprising a pin 25 fixed 10 to and projecting from the bracket 22 and engaged through an oblong slot 26 in the link 21. The lower face of the slide block casing is notched as at 26^a to provide setting points for maintaining the draft door regulating mechanism in its adjusted positions. A spring tensioned catch member 27, consisting of a U-bent plate, engages over the link as a detent and its terminals engage with the notched under surface 26^a, retaining 20 the link and parts connected thereto in their shifted positions. This provides a yielding ratchet check of simple and durable construction. The link 21, at its lower free end connects to the cross cord or chain 12. 25 As the slide or tread block 17 is slid from one end position of the pocket to the opposite end, the links 18 and 21 are approximately rocked, pulling the cord chain connection with the draft doors for the desired draft door regulation.

This enables the draft door actuating mechanism to be connected to the register floor plate, providing a convenient and definite location therefor, establishing uniformity in the installation of the furnaces, as 35 well as simplifying the installation at a reduced cost over the methods now in general practice for mounting the draft door

regulating mechanism upon the room baseboard.

40

Having described our invention, we claim:

1. In a device of the character described, a furnace floor register, furnace draft door actuating means mounted on one side of the floor register, comprising a slide-block slidably mounted in a pocket opening through said register and manually accessible from the face side of the register, and a lever mechanism mounted upon said register, connecting with said slide-block and adapted to be connected with the draft doors of the furnace for controlling the doors at the register.

2. In a device of the character described, a furnace floor register, furnace draft door actuating means mounted on one side of the floor register, comprising a slide-block slidably mounted in a pocket opening through said register and manually accessible from the face side of the register, lever mechanism mounted upon said register, connecting with said slide-block and adapted to be connected with the draft doors of the furnace for controlling the doors at the register, and spring tensioned ratchet check means for said block and lever mechanism for maintaining the same in any adjusted position.

In witness whereof, we hereunto subscribe our names, as attested by the two subscribing witnesses.

GEORGE F. HOLLER.
EMIL SCHMIDT.
